FIG. 1.

FIG. 2.

INVENTOR.
HOWARD E. ROGERS,
BY
H. E. Rogers
ATTORNEY.

UNITED STATES PATENT OFFICE

157,436

PORTABLE STEP DEVICE

Howard E. Rogers, Long Beach, Calif.

Application September 2, 1948, Serial No. 148,444

Term of patent 3½ years

(Cl. D15—8)

To all whom it may concern:

Be it known that I, Howard E. Rogers, a citizen of the United States, residing in Long Beach, county of Los Angeles, and State of California, have invented a new, original, and ornamental Design for Portable Step Device, of which the following is a specification, reference being had to the accompanying drawing, forming a part thereof.

Figure 1 is a perspective front view of the portable step device, showing my new design.

Figure 2 is a perspective rear view of the same.

I claim:

The ornamental design for a portable step device, as shown.

HOWARD E. ROGERS.
